UNITED STATES PATENT OFFICE.

ALBERT ENNIS HENDERSON, OF TORONTO, ONTARIO, CANADA.

ORDNANCE PROJECTILE.

Application filed August 16, 1918. Serial No. 250,135.

The object of the invention is to provide an ordnance projectile, of the shell or other type, and more particularly a means or agency for application to or use in connection with a projectile, and more especially a missile designed for discharge from a rifle bored gun, whereby the trajectory and penetrating capacity are increased by reason of a reduction of the atmospheric resistance to flight incident to cleavage or nose impact and to rear end or backward suction due to the rarefaction of the air at the base of the projectile.

More specifically, the object is to minimize or eliminate the nose pressure or wedge-like spreading or bodily displacement of the air at the forward end of a projectile, by providing for a rotary slicing or cutting and progressive transverse compression or condensation of the air to open a path through which, with the least possible disturbance of adjacent air particles, the projectile may pass with but slight skin friction and practically no rearward suction.

In carrying out the foregoing general objects it is the purpose of the invention in detail

First. To provide a simple and efficient nose piece for any shell which is constructed so as to provide the least resistance to the air.

Second. To provide a nose piece for shells which is adapted to cause an increase in the velocity of flight.

Third. To arrange such nose piece in convenient form for application and securement definitely to a shell.

Fourth. To adapt the form of the nose piece to the varying conditions found in connection with the dimensions and velocities of different shells.

Fifth. To provide means for obliterating the construction of the nose piece after the shell has performed its function or has been exploded.

Sixth. To adapt the nose piece to the ordinary shell in such a manner as not to interfere with the loading or discharging of the shell.

Still further objects and advantages of the invention will appear in the course of the following description of a preferred embodiment, it being understood, however, that various changes in form, proportion

and details may be resorted to, within the scope of the appended claims, without departing from the principles involved.

In the drawings

Figure 1 is a side view, partly broken away, of a shell having a nose piece constructed in accordance with the invention.

Fig. 2 is a transverse sectional view on the plane indicated by A—B of Fig. 1.

Fig. 3 is a similar view on the lines C—D of Fig. 1.

Fig. 4 is a similar view on the line E—F of Fig. 1.

Fig. 5 is a sectional view partly in elevation of the same.

In the form illustrated in Fig. 1 there is employed a shell 6 (broken away at 7 for convenience) having mounted thereon in the usual way a rifling band 8, arranged near the base indicated at 9. Threaded upon the nose 10 of the shell 6 is the nose piece 11 having flanges 12 which are preferably integral therewith, said flanges having their maximum depth near the forward end 12^a of the nose piece adjacent to the line A—B and shown particularly in cross section in Fig. 2.

The flanges 12 are gradually diminished or are reduced in depth progressively as they approach the end 14 of the nose piece, which is coincident with the nose end of the body of the shell, disappearing at the point 15 and in effect merging into the surface of the nose piece in the plane of junction with the nose end of the shell.

The progressive decrease in the depth of the flange 12 is shown graphically by comparison of Figures 2, 3, and 4, representing cross sections at different points in the length of the nose piece.

The flanges 12 are reduced toward their forward and outer edges 16 and 17 to provide for a slicing or cutting action as the projectile progresses and revolves by reason of the gyratory impulse due to the rifling of the bore of the gun from which the same is discharged, and the face or forward surface of each flange is hollowed or concaved as shown at 18 with the object of definitely separating the core of air necessary to provide a path for the body of the projectile from the surrounding mass or stratum of air, under conditions tending to minimize the radial movement of the particles of air due to centrifugal force. the nose piece as constructed has the effect of penetrating the air in what may be regarded as a boring action, to the end that while there is a local lateral compression or condensation throughout a zone representing the path as defined by the diameter of the projectile, the body of the air in proximity to this path remains substantially undisturbed, with the incidental, though important result that the tendency to form a vacuum or atmospheric rarefaction at the rear end or base of the shell, and which ordinarily has a restraining effect, due to suction, is minimized.

In contradistinction to the progressive rearward reduction of the areas of the wings representing an essential part of the path-forming nose piece, the body or cone 19 from which said wings project radially is progressively reduced in a forward direction from a diameter corresponding with the nose end of the shell to a vanishing point at the forward extremities of said wings.

In Fig. 5 there is shown in section the nose of the shell exteriorly screw-threaded as at 21 to engage the interiorly threaded portion 22 of the nose piece, and formed in these engaging elements as at 23 is a seat 24 for the reception of a threaded locking pin 25.

Also centrally located in the nose piece is a conical cavity or recess 26 bounded at its rear end by a cross head 27 having an opening 28 for the reception of a fuse plug 29, designed to detonate a charge of explosive 30 contained in the cavity 26 for the purpose of destroying the nose piece on the explosion of the shell to prevent discovery of its structure by the enemy. Obviously a time fuse may be employed in connection therewith and the cavity 31 in the base of the nose piece will form a suitable housing for the same.

As in the ordinary practice the rotary or gyratory movement of the projectile will be received from the rifling of the gun bore acting through the band 8 and it is proposed that with a given pitch of rifling grooves, causing a given gyratory velocity, and with a given muzzle velocity due to the powder charge the pitch of the spiral flanges on the nose piece shall correspond approximately with the resultant of the two motions, to the end that the progress of the projectile shall be effected with the minimum skin friction upon the flanges, but obviously variations in one direction or the other in the matter of ratio of progressive movement to gyratory movement may be adopted to suit conditions under which the projectile is to be employed, with the result that if there is deviation in one direction or the other of the pitch of the wings from a true resultant of the two movements, the tendency will be either to increase the trajectory by reason

of the propeller action or to increase the speed of rotation due to the reaction of the air displaced.

It will be noted that the diameter of the nose piece as an entirety is less than that of the shell, as indicated graphically by the dotted line G—H and the intersection thereof with the diametrical line A—B, to provide for ample clearance of the nose piece within the bore of the gun to avoid frictional contact therewith.

Obviously the pitch of the flange and the length of the nose piece may be varied, as also may the curve 18 representing the concavity which in turn determines the relative cutting action and transverse compression or condensation of the air displaced.

From the foregoing description it will be obvious that in operation the flanges or wings serve in the capacity of blades of which forward or penetrating edges are reduced to cutting dimensions while the lateral or exterior edges which are preferably continuous and extend on lines at a substantially uniform distance from the axis of the projectile and at a projection therefrom which is only slightly less than the radius of the projectile, are similarly reduced to cut or slice the air, the outermost portions of the lateral blade edges being directed forwardly with reference to the path of rotation to accentuate the cutting action and the extent of this forward deflection being at its maximum at the forward ends of the blades and being progressively reduced rearwardly therefrom.

Having described the invention, what I claim is—

1. A fixed nose piece for projectiles having concave-convex flanges at an angle to the line of the axis of the projectile, substantially as set forth.

2. A fixed nose piece for projectiles having flanges of concave formation on the side in the direction in which the projectile rotates, and having a corresponding convex formation on the opposite side of the flange, substantially as set forth.

3. A fixed nose piece for projectiles having concave-convex flanges disposed at an angle to the axis of the projectile, said flanges tapering backward from a point in line with the axis of the shell, substantially as set forth.

4. A nose piece for projectiles having concave-convex flanges disposed at an angle to the axis of the projectile and gradually reducing in thickness outwardly, substantially as set forth.

5. A nose piece for projectiles having concave-convex flanges gradually reducing rearwardly in depth, substantially as set forth.

6. A nose piece adapted to be fixedly attached to the forward end of a projectile said nose piece being of less diameter than

the body of the projectile, and concave-convex flanges thereon terminating in lateral and forward cutting edges, substantially as set forth.

5 7. A nose piece for projectiles having oppositely disposed concave-convex flanges terminating in forward and lateral cutting edges the flanges gradually decreasing in thickness from their bases to their outer 10 edges, substantially as set forth.

15 8. A nose piece for projectiles having concave-convex flanges rearwardly merging into the body of the nose piece and tapering rearwardly from a point in the line of the 20 axis of the projectile, substantially as set forth.

9. A nose piece for projectiles having concave-convex outwardly tapering rearwardly reducing flanges adapted to penetrate the air 25 or any fluid mediums with the minimum of resistance and adapted to temporarily separate the penetrated air or other fluid from

the surrounding fluid body, substantially as set forth.

10. A fixed nose piece adapted to engage 25 the forward end of a projectile said nose piece having concave-convex flanges terminating in forward and lateral cutting edges, a receptacle therein for explosive material, and means for detonating the same to obliterate 30 the form of the said nose piece, substantially as set forth.

11. A device of the kind described comprising a body having spiral flutes formed therein beginning at a substantially intermediate point and continuing to one extremity and gradually increasing in depth from the point of beginning to said extremity, the upper walls of the flutes forming 35 arcuate wings for wiping action against 40 the wind when the device is rotated when fired.

ALBERT ENNIS HENDERSON.
